Patented Mar. 19, 1918.

Inventor

ARTHUR G. KENT

By *Watson E. Coleman*

Attorney

UNITED STATES PATENT OFFICE.

ARTHUR G. KENT, OF ROCHESTER, NEW YORK.

CLOTHES-DRIER.

1,260,206.

Specification of Letters Patent. Patented Mar. 19, 1918.

Application filed July 23, 1917. Serial No. 182,319.

To all whom it may concern:

Be it known that I, ARTHUR G. KENT, a citizen of the United States, residing at Rochester, in the county of Monroe and 5 State of New York, have invented certain new and useful Improvements in Clothes-Driers, of which the following is a specification, reference being had to the accompanying drawings.

10 This invention relates to certain improvements in clothes driers and it is an object of the invention to provide a novel and improved device of this general character including a plurality of pivotally supported 15 arms mounted for movement in a vertical direction and wherein the pivoted end portion of each of the arms is capable of vertical adjustment independently of the remainder of the arms.

20 It is also an object of the invention to provide a device of this general character which includes a supporting plate provided with an elongated trackway or guide rod and with which is slidably engaged a bracket 25 carrying a supporting arm and wherein said bracket is provided with means for locking the same at different positions longitudinally of the trackway or guide rod.

The invention consists in the details of 30 construction and in the combination and arrangement of the several parts of my improved clothes drier wherein certain important advantages are attained and the device rendered simpler, less expensive and other- 35 wise more convenient and advantageous for use, as will be hereinafter more fully set forth.

The novel features of my invention will 40 hereinafter be definitely claimed.

45 In order that my invention may be the better understood I will now proceed to describe the same with reference to the accompanying drawings wherein—

Figure 1 is a view in side elevation of a 50 drier constructed in accordance with an embodiment of my invention;

Fig. 2 is a view in front elevation of the device as herein disclosed;

Fig. 3 is an enlarged fragmentary view 55 partly in elevation and partly in section illustrating in detail the co-action between a guide rod and bracket as herein disclosed and illustrating a fragment of a supporting bar in lowered or operative position; and

Fig. 4 is a fragmentary view in perspective illustrating one of my improved brack-

ets as herein set forth and a co-acting portion of the guide rod.

As disclosed in the accompanying drawings 1 denotes an elongated plate adapted 60 to be supported adjacent a stove or other heat generating unit and said plate is provided adjacent its opposite ends with the brackets 2. Interposed between the brackets 2 and supported thereby are the guide rods 65 3 arranged substantially in parallelism and positioned a predetermined distance in advance of the plate 1.

Slidably engaged with each of the guide rods 3 is a bracket B and as herein disclosed 70 said bracket B comprises a rear plate 4 having its upper end portion provided with an outwardly directed tongue 5 at substantially right angles to the plate 4 and which is provided with an opening 6 through which the 75 rod 3 is directed. The opposite or lower end portion of the plate 4 is provided with an elongated tongue 7 returned upon itself on a predetermined curvature and provided with openings 8 through which the rod 3 is 80 also directed. The free end portion 9 of the tongue affords a finger piece. The elongated tongue 7 possesses sufficient inherent resiliency as to cause the walls of the openings 8 to frictionally engage the rod 3 in such a 85 manner as to effectually hold the bracket B against movement longitudinally of the rod 3. When it is desired to move the bracket B along the rod 3 the finger piece 9 is forced upwardly which results in the openings 8 90 being so alined as to permit the bracket B to be freely moved upon the rod 3.

The bracket B also embodies the forwardly directed side plates 10 which extend a predetermined distance above the plate 4 95 and which have their lower edges defined by the inwardly directed flanges 11. Extending between the side plates 10 is an end portion of a bar 12 which is pivotally engaged with said plates 10 by the transverse 100 pin 14. The pin 14 is so positioned relative to the flange 11 as to cause a longitudinal edge of the bar 12 to rest upon the flanges 11 when the bar 12 is in substantially a horizontal position so that said bar will be maintained in said position when desired for use. When the bar 12 is not in use the same is 105 swung upwardly into substantially a vertical position and is automatically maintained in such position by the frictional contact 110 therewith of the side plates 10. The outer margins of the plates 10 have their upper

portions 15 outwardly inclined so that as the bar 12 is moved upwardly the forward margins of the plates 10 are separated to permit the passage of the bar therebetween but when the bar 12 assumes substantially a vertical position the plates 10 will spring back to a position to frictionally engage the side faces of said bar 12 and thereby hold the same against downward movement.

10 From the foregoing description, it is thought to be obvious that a clothes drier constructed in accordance with my invention is particularly well adapted for use by reason of the convenience and facility with which it may be assembled and operated and it will also be obvious that my invention is susceptible of some change and modification without materially departing from the principle and spirit thereof and for this reason I do not wish to be understood as limiting myself to the precise arrangement and formation of the several parts herein shown in carrying out my invention in practice except as hereinafter claimed.

20

25

I claim:

1. A clothes drier comprising a guideway, a bracket slidably engaged with the guideway and provided with means for normally holding the same against movement longitudinally of the guideway, a bar pivotally engaged with the bracket, said bracket being provided with means co-acting with the bar for limiting the same against movement beyond substantially the horizontal, said bracket being also provided with means for holding the bar substantially vertical.

2. A device of the character described including a bracket provided with side plates, the lower margins of the side plates being

defined by inwardly directed flanges, a bar 40 interposed between the plates and pivotally supported thereby, said bar contacting with the inwardly directed flanges when at its limit of movement in one direction, said side plates frictionally engaging the bar 45 for maintaining the bar at substantially its limit of movement in an opposite direction.

3. A device of the character described comprising a guide rod, a bracket provided with a perforate tongue through which the 50 guide rod is disposed and with a second elongated resilient tongue returned upon itself on a predetermined curvature, said tongue being provided with openings through which the guide rod is disposed, the 55 free end portion of said elongated tongue serving as a finger piece, and a bar operatively engaged with the bracket.

4. A device of the character described including a bracket provided with side plates, 60 the lower margins of the side plates being defined by inwardly directed flanges, a bar interposed between the plates and pivotally supported thereby, said bar contacting with the inwardly directed flanges when at its 65 limit of movement in one direction, said side plates frictionally engaging the bar for maintaining the bar at substantially its limit of movement in an opposite direction, the upper marginal portion of the side plates 70 being outwardly inclined.

In testimony whereof I hereunto affix my signature in the presence of two witnesses.

ARTHUR G. KENT.
